H. B. OVES,
DISH WASHING MACHINE,
APPLICATION FILED MAR. 23, 1920.

1,381,221.

Patented June 14, 1921.

UNITED STATES PATENT OFFICE.

HENRY BUCHLER OVES, OF ERIE, PENNSYLVANIA.

DISH-WASHING MACHINE.

1,381,221.

Specification of Letters Patent. Patented June 14, 1921.

Application filed March 23, 1920. Serial No. 368,014.

To all whom it may concern:

Be it known that I, HENRY B. Oves, a citizen of the United States, and a resident of Erie, in the county of Erie and State of Pennsylvania, have invented certain new and useful Improvements in Dish-Washing Machines, of which the following is a specification.

My invention is an improvement in dish washing machines, and has for its object to provide a machine of the character specified, capable of attachment to an ordinary water faucet, and having a circular brush adapted to be rotated by the flowing water, and carrying a soap chamber which is rotated by the flowing water and through which the water flows to deliver the detergent to the brush.

In the drawings:—
Figure 1 is a vertical section of the improved washer,

Figs. 2, 3, 4 and 5 are sections on the lines 2—2, 3—3, 4—4, and 5—5, respectively of Fig. 1.

In the present embodiment of the invention, a suitable casing is provided, consisting of a tubular portion 1 having each end annularly enlarged as shown at 2 and 3, the former enlargement furnishing a portion of a casing for a motor, and the latter, a portion of a casing for a soap chamber.

The casing is completed by a head 4 and a cylindrical brush body 5. The head 4 is secured to the enlargement 2, the enlargement and head having marginal flanges 6 provided with registering openings 7 for receiving bolts to connect the head to the casing, and this head has an axial inlet 8 which may be connected with an ordinary water faucet.

From the inlet, a passage 9 leads to an annular chamber 10 within the motor casing formed by the enlargement 2 and the head 4, the said chamber being formed by annular grooves in the head and the enlargement as shown in Fig. 2.

Ports 11 extend from the annular passage 10 into the motor casing, and referring to Fig. 2, it will be seen that all of these passages are inclined, delivering in the same direction and at an angle to radii of the casing. A shaft 12 is held at the axis of the body portion 1 of the casing, by means of bearings 13 and 14 arranged at the top and bottom of the said body, and the said bearings are supported by the body in spaced

relation, by means of spirally arranged webs 15 and 16, respectively.

Referring to Figs. 3 and 4, it will be seen that all of these webs are inclined in the same direction, and they tend to impart a whirling motion to the water about the axis of the casing 1—2—3. A series of radial blades 17 is connected with the shaft above the bearing 13, the said blades having a hub 18 portion which is received on a reduced portion at the upper end of the shaft 12, and held by a nut 19.

Referring to Fig. 2, it will be seen that the passages 11 incline in a direction to cause the water to impinge against the blades, almost perpendicularly as they pass the passages, and will rotate the shaft 12. A soap chamber 20 is secured to the lower end of the shaft, the soap chamber being a cup-shaped casing, and the shaft has a reduced portion 21 which passes through an opening in the top of the chamber and is engaged by a nut 22 below the top of the chamber.

The soap chamber has openings or ports 23 in its upper end, which register with the space between the webs 16 to permit water to flow from the body 1 of the casing into the soap chamber. Referring to Fig. 1, it will be seen that the bearing 14 is spaced 85 below the connection of the enlarged portion 3 of the body of the casing 1, and that the ribs 16 are connected at their outer edges by an annular web 24. This web tapers toward its lower end, and the openings are 90 between the lower end of the web and the bearing 14. Between the web and the wall of the enlargement 3, there is an annular space within which engages an annular rib or extension 25 on the upper end of the soap 95 chamber, the adjacent walls of the rib and of the web fitting each other.

The soap chamber has near its lower end an external annular groove 26 which is formed by an internal bead and of a depth 100 to completely receive a split ring 27 of resilient material. The brush body 5 has an internal annular groove 28 with which this ring 27 is adapted to engage to act as a key to lock the brush from movement longitudinally with respect to the soap chamber.

When the ring is contracted into the groove 26, it will be evident that the brush may be pushed onto the chamber over the ring. When the brush is in place the ring 110 will expand and will lock the parts together. Referring to Fig. 1, it will be seen that that

portion of the internal surface of the brush above the groove 28 is beveled in both directions to facilitate the placing and the removal of the brush.

The brush has a vertical groove or keyway 29 with which is adapted to engage a key 30 on the soap chamber, to prevent relative angular movement of the brush with respect to the soap chamber. Referring to Fig. 1, it will be seen that the brush is approximately cup-shaped, provided with an annular series of bristles 31 on its side wall and with other bristles 31 at its end, and that passages 32 are provided leading from the interior of the soap chamber and brush to the end of the brush, delivering among the tufts of bristles.

Inside the passages 32 the internal surface of the end of the cup-shaped brush is rounded as shown at 33. A hollow handle 34 is connected with the head 4, the handle extending radially therefrom, providing a means for supporting the washer.

In operation, the dishes to be washed are placed in a suitable container, and the inlet pipe 8 is connected with a source of water supply as through the medium of a rubber tube. The water flows through this pipe and through the passage 9 into the annular passage 10 and by way of inclined ports 11 into the motor chamber where it impinges against the blades 17 and causes the motor to rotate. The waste water passes between the ribs 15 and on down to the casing 1 and between the ribs 16 into the soap chamber.

From here the water laden with the soap passes through the ports 32 into the bristles and onto the dishes to be washed. By means of the handle, the brush may be brought into engagement with every part of the dishes, which while they are sluiced with water, containing the detergent are also brushed with the bristles, thoroughly cleaning the same. In practice, the blades 17 will be of brass, as will also the shaft 12. The soap chamber and casing will be of aluminum. When it is desired to remove the brush, it is only necessary to draw the same longitudinally with respect to the shaft. The bevel springs the ring inward, and the brush may thus be removed.

I claim:—

1. A device of the character specified, comprising a casing having at one end an enlargement for receiving a soap chamber, and at the other end an enlargement for receiving a motor, a shaft having one end in the motor chamber and the other in the enlargement, a cup-shaped soap chamber connected to the

shaft at the last named end, a water motor connected to the shaft in the motor chamber, said chamber having an inlet for the water, and a brush body, having external bristles, detachably connected with the lower end of the soap chamber to rotate therewith, and having outlets for the water and the soap, bearings in the casing for the ends of the shaft and spaced apart from the casing wall, and ribs connecting the bearings to the casing wall, all of said ribs being spirally arranged.

2. A device of the character specified, comprising a casing having at one end an enlargement for receiving a soap chamber, and at the other end an enlargement for receiving a motor, a shaft having one end in the motor chamber and the other in the enlargement, a cup-shaped soap chamber connected to the shaft at the last named end, a water motor connected to the shaft in the motor chamber, said chamber having an inlet for the water, and a brush body detachably connected with the lower end of the soap chamber to rotate therewith, and having outlets for the water and the soap.

3. A dish washing machine, comprising a casing adapted for connection at one end with a source of water supply and to receive at the other end a soap chamber having ports through which the water may flow from the casing through the soap chamber, means controlled by the flow of the water for rotating said soap chamber within the casing, and a brush body detachably connected with the soap chamber.

4. A device of the class described, comprising a casing having at one end an enlargement for receiving a soap chamber, and at the other end an enlargement for receiving a motor, a shaft having one end in the motor chamber and the other end in the enlargement, a cup-shaped soap chamber connected to the shaft in the last named end and having an open end disposed downwardly, a water motor connected to the shaft in the motor chamber, said chamber having an inlet for the water, and a brush body having external bristles detachably connected with the lower end of the soap chamber to rotate therewith, said brush body fitting over the lower projecting end of the soap chamber and having outlets for the water and the soap, the motor chamber being provided with an annular passage outside of the same having inlet ports to the motor chamber inclined in the same direction.

HENRY BUCHLER OVES.
